UNITED STATES PATENT OFFICE.

VICTOR E. EDWARDS, OF WORCESTER, MASSACHUSETTS, ASSIGNOR TO THE MORGAN CONSTRUCTION COMPANY, OF SAME PLACE.

WIRE-DRAWING MACHINE.

SPECIFICATION forming part of Letters Patent No. 543,858, dated August 6, 1895.

Application filed July 8, 1893. Serial No. 479,968. (No model.)

To all whom it may concern:

Be it known that I, VICTOR E. EDWARDS, a citizen of the United States, residing at Worcester, in the county of Worcester and State of Massachusetts, have invented a new and useful Improvement in Wire-Drawing Machines, of which the following is a specification, reference being had to the accompanying drawings, forming a part of the same, and representing a wire-drawing machine embodying my invention, in which—

Figure 1 represents a perspective view of the machine. Fig. 2 is a plan view of the same. Fig. 3 is a vertical sectional view on line 3 3, Fig. 2. Fig. 4 is a central sectional view of the drawing-block carried upon the end of one of the conical drawing-drums, the section being taken on line 4 4, Fig. 5. Fig. 5 represents an end view of the drawing-block in section shown in Fig. 4, the hand-wheel having been removed on line 5 5, Fig. 4; and Fig. 6 is a sectional view of the gripping-jaws on line 6 6, Fig. 5.

Similar letters and numerals refer to similar parts in the different figures.

My invention relates to certain improvements in that class of wire-drawing machines in which the wire is drawn through several successive dies in a continuous operation; and it consists in the several features herein-after described and specifically pointed out in the annexed claims.

Referring to the accompanying drawings, A denotes the supporting stand or framework, in which is journaled a horizontal driving-shaft A', provided with tight and loose pulleys A² A³, and a pinion A⁴, engaging gears A⁵ A⁶ upon the shafts B and B', journaled in the framework of the machine and carrying conical wire-drawing drums B² and B³, provided with circumferential V-shaped grooves B⁴. The shaft B carries the bevel gear B⁵, which engages a bevel-gear upon the vertical shaft C, journaled in the framework of the machine and provided with a spur-gear C', engaging a spur-gear C², attached to the drawing-block C³, which rotates upon a stud C⁴, held in an arm C⁵, projecting from the framework of the machine.

Supported by the framework of the machine and between the conical drawing-drums

B² and B³ is a die-box or trough D, with its bottom D' inclined to correspond with the taper of the conical drawing-drums B² and B³. The die-box D is provided with a central partition D², which, with the side walls D³ and D⁴, is provided with vertical slots D⁵, placed in alignment with the V-shaped grooves B⁴ on the conical drawing-drums B² and B³, allowing the wire in the operation of drawing to pass from one of the drawing-drums to the other through the slots D⁵, and also through reducing-dies E, which rest against the central partition D² and the side wall D³ of the trough D, by which the dies E are held from longitudinal movement as the wire is drawn through them. The die-box D is also provided with a series of transverse partitions F, extending across each of the two divisions of the die-box between each set of dies, forming separate compartments F', each containing a reducing-die E.

Attached to the end of the wire-drawing drum B² is a plate G, provided at its periphery with a gib G', inclosing the edge of a flange G² upon a drawing-block G³. (Shown in central sectional view in Fig. 4 and in end view in Fig. 5.) The drawing-block G³ is provided with a concentric sleeve G⁴, loosely fitting the end of the shaft B and provided with an internal screw-thread G⁵ to receive a screw G⁶, having a central screw-threaded hole, in which is carried a screw G⁷, provided with a tapering point G⁸, which enters a countersunk depression G⁹ in the end of the shaft B. The plate G is made in halves, so as to be applied to the flange G², and is attached to and rotated with the conical drawing-drum B², and the drawing-block G³ is capable of turning within the annular gib G', thereby allowing the drawing-block to remain at rest during the rotation of the drum B² and plate G. The screw G⁷ is provided with a hand-wheel G¹⁰, by which the screw is turned and pressed against the end of the shaft B² to draw the block G³ off the end of the shaft B and crowd the inclined surface G¹¹ against the gib G', in order to produce a frictional resistance sufficient to cause the drawing-block G³ to be rotated with the plate G.

The end of the drawing-block G³ is provided with a recess G¹² to receive a wire-gripping

device carried by the drawing-block and pivoted thereto by means of a screw G^{13} .

The gripping device consists of a jaw H , formed of a bar pivoted upon the screw G^{13} 5 and provided with teeth H' , and a jaw H^2 , provided with lugs H^3 , which are pivoted to the jaw H by a pin H^4 . The jaw H^2 is provided with a tail-piece H^5 , extending rearwardly, to which pressure is applied to rock the jaw H^2 10 on its pin H^4 and separate the jaws to insert the wire, and between the rear wall H^6 of the pivoted jaw H^2 and the shoulder H^7 on the jaw H is placed a spring H^8 , with its tension exerted upon the pivoted jaw to rock it upon 15 the pin H^4 and carry the teeth H^9 forward and downward toward the teeth H' , so that the end of a wire inserted between the teeth H' and H^9 will be securely held, as the tensile strain exerted upon the wire will tend to carry 20 the teeth H^9 of the pivoted jaw forward, rocking the jaw upon the pin H^4 , and the forward motion of the teeth H^9 , caused by the angular motion of the jaw on the pin H^4 , will cause the teeth H^9 to approach the teeth H' and 25 engage the wire held between them, the initial bite of the teeth upon the wire being due to the pressure of the spring H^8 .

The drawing-block G^3 is provided with a curved surface I , leading from the recess G^{12} 30 to the circular face or periphery I' of the drawing-block, the curved surface I being tangential to the periphery I' and also to a straight line passing through the center of the screw G^{13} , which represents the line of 35 draft of the wire as held between the jaws H H^2 . A flange J projects from the frontside of the die-box, forming a platform or shelf, which supports a swinging bar J' , pivoted to the flange J at J^2 and having at its free end 40 two upright prongs J^3 J^3 , against which one of the dies E is placed, for the purpose of holding the die from longitudinal movement as the wire is drawn through it.

In the operation of the machine the wire is 45 successively reduced in diameter by the several reducing-dies in their numerical order, the first reduction being made by die 1, the second by die 2, and so on, and in order to introduce the wire to the machine the diameter of the wire must be reduced to correspond 50 to each of the dies—that is, it must be reduced in diameter sufficiently to pass through die 1, around the conical drawing-drums B^2 and B^3 , and further reduced to pass through die 2, and again around the conical drawing-drums B^2 and B^3 , and still further reduced to pass through die 3, and so on through the successive dies and around the drawing-drums B^2 B^3 to the drawing-block C^3 , upon which it 55 is wound in the usual manner, the periphery of the drawing-block being tangential to the line of wire as it is delivered from the last V-shaped groove in the conical drawing-drum B^3 . The several dies from 1 to 8, inclusive, 60 are held within the compartments F' of the die-box and against the side wall D^3 and central partition D^2 , and the last die 9 is held by

a supporting-bracket placed outside the die-box for lack of room within the die-box.

The successive reductions of the wire necessary to introduce it to the reducing-dies are accomplished by pointing the end of the wire and passing it through the larger of the dies or die 1 and seizing the pointed end by the gripping-jaws H H^2 , with the die 1 placed upon the swinging bar J and against the upright prongs J^3 J^3 . The block G^3 is then rotated by turning the hand-wheel G^{10} and operatively connecting the block with the plate G , carried by the rotating drawing-drum B^2 . As the block G^3 rotates, the wire is held by the gripping-jaws H H^2 , is conducted over the curved surface I upon the circular face I' of the block G^3 , and a sufficient quantity is wound thereon to fill the drawing-drums B^2 B^3 , the swinging-bar J , carrying the reducing-die, allowing the wire to be traversed upon the block G^3 . The wire is then removed from the block G^3 , the die 1 placed in position in the die-box, and the end of the wire again pointed and passed through die 2, which is held upon the swinging bar J , and the wire is seized by the gripping-jaws H H^2 and the operation again repeated, and so on through each of the reducing-dies successively until the wire is carried through each of the dies and around the drawing-drums B^2 B^3 with the dies held in position in the compartments F^2 of the die-box D , as represented in Fig. 2 of the drawings.

Beneath the drawing-drums B^2 B^3 , I place a receiving-pan K , provided with a strainer K' , communicating with a trough K^2 , containing a lubricating-liquid, which is forced from the trough K^2 upward through a pipe K^3 by the revolution of a centrifugal pump K^4 and delivered to the die-box D , filling the upper of the compartments F' and flowing over the highest of the transverse partitions F to the next lower compartment, thence over the next transverse partition to the next lower compartment, and so on through the several compartments of the die-box, the final overflow falling into the receiving-pan K and through the strainer K' to the trough K^2 .

The sides of the die-box D are provided with aprons L L , which extend partially over the drawing-drums B^2 B^3 , so that the lubricating liquid escaping from the die-box through the slots D^5 is delivered upon the drawing-drums B^2 B^3 , lubricating the surfaces of the drums and dripping from them into the pan K . The centrifugal pump K^4 is driven by a vertical shaft K^5 and pulley K^6 by a belt connection from an overhead or counter shaft, the belt connection being carried around the idle-pulleys K^7 K^7 .

The vertical pipe K^3 is provided with a valve at K^8 , operated by a valve-stem K^9 , extending to the front of the machine, by which the flow of liquid through the pipe K^3 is regulated. Whenever a change in the size of the wire to be drawn is necessary to vary the diameter of the drawing-block C^3 , the axis of

the block is changed so as to bring its actuating-gear in mesh with the gear C' and also bring its periphery tangential to the line of wire as delivered to the drawing-drum B³, and this is accomplished by providing the arm C⁵, upon which the drawing-block is supported, with a series of holes M, adapted to receive the stud C⁶.

The arrangement of the die-box D, placed at an inclination and provided with a series of transverse partitions, causes the lubricating liquid pumped into the highest of the compartments to flow over the tops of the partitions F, which serve as dams, producing an agitation of the liquid throughout each of the compartments, at the same time retaining a body of liquid in each compartment sufficient to completely immerse the wire.

The gripping-jaws H¹ and H² can be raised out of the recess G¹² by rotating them upon their pivotal screw G¹³, in order to allow the end of the wire to be inserted; but when the block G³ is rotated in the operation of winding wire thereon the gripping-jaws occupy the position represented in Fig. 5, lying wholly within the arc of the circle describing the periphery of the block G³, so that as the wire is traversed across the face of the block and wound against the flange G² the coils of wire already wound upon the block will be pushed toward the end and over the recess G¹², thereby utilizing the entire face I' for the wound wire.

What I claim as my invention, and desire to secure by Letters Patent, is—

35 1. In a wire drawing machine, the combination with a pair of wire drawing drums, of an inclined die box placed between said drums, a series of dies held in said die box at different vertical planes, and means for feeding lubricating liquid to said die box at its highest side, whereby said lubricating liquid is caused to flow over said dies in succession, substantially as described.

45 2. In a wire drawing machine, the combination with a pair of wire drawing drums, of a die box placed between said drums and in an inclined position, means for feeding lubricating liquid to its highest side, whereby said liquid is caused to flow over said inclined die box, and a series of partitions placed transversely to the flow of said liquid over the surface of the die box, whereby said stream is impeded, and a series of dies held in the spaces between said partitions, substantially as described.

55 3. In a wire drawing machine, the combination of wire drawing drums, an inclined die box arranged to receive a flowing stream of lubricating liquid, transverse partitions of varying vertical height forming a series of dams over which said stream flows, and a series of dies held in said box, substantially as described.

4. In a wire drawing machine, the combination with a pair of wire drawing drums, of a die box held between said drums, and hav-

ing side walls, as D³ and D⁴, parallel with the axes of said drums, means for feeding lubricating liquid to said die box and aprons, as at L, extending from the sides of said die box over said drums, whereby the overflow at the sides of said die box is conducted to and delivered upon said drums, substantially as described.

5. In a wire drawing machine, the combination of a pair of wire drawing drums, a wire block carried upon the end of one of said drums, wire gripping mechanism carried by said wire block and a pivoted die holding lever, capable of an angular motion by which the wire is allowed to traverse upon said block, substantially as described.

6. In a wire drawing machine, the combination of shaft B, a plate G concentric with said shaft and having a gib G', a wire block G³, held by said plate, and having a sleeve G⁴ inclosing said shaft and a screw G⁷ carried by said block and acting against the end of said shaft to operatively connect the block and plate, substantially as described.

7. The combination with a drawing block of a bar H pivoted at one end to said block and having teeth H' at its opposite end arranged in a plane corresponding with the line of draft, a jaw H⁵, provided with teeth H⁹ arranged in a plane corresponding with the line of draft, lugs H⁸ projecting from the jaw H², at right angles to the plane of the teeth and pivoted at their ends to said bar H, said bar H having a shoulder H⁷, and said jaw H² having an opposing wall H⁶, a spring inserted between said shoulder and said wall to close the teeth of the jaw upon the teeth of said bar and a projecting tail piece H⁵, by which the jaw is opened, substantially as described.

8. In a wire drawing machine, the combination with a pair of wire drawing drums, of a die box placed between said drums having aprons L, L, extending from the sides of said box over said drums, a receiving pan K beneath said drums, a strainer K', a trough K², pipe K³, pump K⁴, valve K⁸, in the pipe K³ and a valve stem K⁹ extending from the valve K⁸ to the front of the machine, substantially as described.

9. In a wire drawing machine, the combination of a pair of conical wire drums B² and B³, carried on the projecting ends of shafts B and B² having parallel axes, a die box placed above the plane of said shafts and at an inclination corresponding to the inclination of the upper sides of said conical drums, said box having side walls D³ and D⁴, provided with openings to receive the wire, transverse partitions at right angles to said side walls, and dies held between said transverse partitions, substantially as described.

Dated this 6th day of July, 1893.
